MULTIPLE WEAVE MOTION FOR LOOM DOBBIES

Filed June 21, 1926

UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

MULTIPLE-WEAVE MOTION FOR LOOM DOBBIES.

Application filed June 21, 1926. Serial No. 117,291.

This invention relates to improvements in multiple weave motions for looms and it is the general object of the invention to provide a continuously running auxiliary pattern chain with indicating levers which are attached by flexible connections to another set of levers controlled by the main pattern chain whereby when desired the effect of the first or auxiliary chain can be nullified to permit a control of the harnesses by the main pattern chain.

The invention relates more particularly to the type of dobby set forth in patent to Selley No. 955,559. In the motion disclosed in said patent there is provided an upper constantly moving auxiliary cylinder having a pattern chain to actuate a set of auxiliary levers which are flexibly connected to a lower set of levers raised and lowered by the main pattern chain. The connections shown in said patent are such that the harnesses and lower levers which are attached to the upper levers cannot be used except as they are called into action by the upper levers or except as the non-peggng of the upper chain will permit lifting of the lower fingers. For this reason it is impossible for all practical purposes to use those levers of the lower set which are assigned to the upper set and it is an important object of my invention to provide a device which will ordinarily lengthen the path traversed by the cords which connect the upper and lower levers so that when the device is operative the lifting of an upper lever will raise the corresponding lower lever, but when said device is moved to slacken the cord the upper levers can move without producing any effect on the lower levers, thereby freeing the latter to be acted upon by another pattern surface having a weave or box indication different from that of the upper chain.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a front elevation of a dobby

located at the left hand end of a loom and having my invention applied thereto,

Fig. 2 is a side elevation taken in the direction of arrow 2, Fig. 1, the cylinders being shown in section and the pattern chain being removed for the sake of clearness,

Fig. 3 is a vertical section on line 3—3 of Fig. 2, certain parts being omitted for the sake of clearness,

Fig. 4 is an enlarged fragmentary vertical section taken on line 4—4 of Fig. 3, and

Fig. 5 is a detail view showing the controller for the cords taken in the direction of arrow 5, Fig. 2.

Referring to the drawings the dobby frame 10 has journaled therein a shaft 11 on the front and rear ends of which are secured rocker arms 12 one of which is shown in the drawings. The lower portion of said frame 10 has journaled therein a shaft 13 to which is secured the lower or main chain cylinder 14 having a pattern chain 15. A ratchet wheel 16 secured to the shaft 13 has teeth disposed in such a direction as to cause angular movement of the shaft when the rocker arm 12 moves in a counterclockwise direction through the action of pawl 17. Said pawl is pivoted to the rocker arm 18 and will move the cylinder for a distance equal to one space on the pattern chain 15 on alternate picks of the loom.

The mechanism for determining whether pawl 17 shall be operatively disposed with regard to ratchet 16 includes a pin 19 extending laterally from the pawl and lying over a lifter wire 20, the outer or left hand end of which as shown in Fig. 1 is mounted on a lug 21 projecting forwardly from a special lever 22 pivoted on a shaft 23 secured in the dobby frame. Said lever 22 is positioned to be acted upon by a portion of the main pattern surface. The other end of wire 20 is supported on a stud 24 extending forwardly from the inner end of a lever 25 pivoted as at 26 to the loom frame and connected by a link 27 to a lifting lever 28 pivoted to the upper part of the dobby frame.

The position of the lifting lever 28 is determined by an auxiliary single space multiplier chain 29 carried on a sprocket 30 keyed or otherwise secured to a shaft 31 to

which is also secured the upper auxiliary cylinder 32. The shaft 31 receives a regular angular motion during the operation of the loom, this motion being either intermittent or continuous and may be given as set forth in the aforesaid patent. It is sufficient for the purposes of the present description to state that the cylinder 32 will receive an angular motion every second pick of the loom so that the pattern chain 34 carried thereby will present a new bar under the auxiliary levers 35 every second pick of the loom.

A lower or main set of levers 36 lies over the chain 15 and will be controlled as to vertical position by the latter. Connecting cords 37 connect the upper and lower levers 35 and 36 in pairs and the lower levers are connected, by mechanism not shown but well understood, to the dobby hooks (not shown) which actuate the harness frames of the loom in connection with regularly but oppositely reciprocating dobby knives (not shown). These cords correspond to the wires performing a similar function in the aforesaid patent.

The pattern chain 29 is provided as shown herein with one high ball 38 which will raise lever 28 once for each revolution of chain 29, the motion being accompanied by a downward motion of the stud 24 and the inner end of wire 20. If this motion coincides with a blank space on the lower chain under lever 22 then wire 20 will be in its lowest position and will permit pin 19 and therefore pawl 17 to move downwardly so that the latter will be able to move the chain 15. The operation of the matter thus far described is the same as that set forth in the aforesaid Selley patent, and a further description of the same is considered unnecessary.

In carrying out my improvements I provide means for acting on the cords 37 so that at times the upper levers 35 can control the lower levers and at other times said upper levers will be ineffective to control the lower levers. In carrying out my invention I provide the dobby frame with a stand 50 on which is mounted for free pivotal motion a tensioning device 51 having a stud 52 extending through the hub 53 of the stand 50 and having upper and lower arms 54. Each of said arms has extending therethrough a tensioning rod 55 which is held in proper longitudinal position by a set screw 56. Said rods 55 are slidable in the arms 54 so as to be operatively disposed with regard to a greater or lesser number of the cords 37 according to the conditions of any particular weave or box sequence. A light wire 57 extends between the ends of the rods 55 to prevent the cords when slack from passing out of control of the rods.

The tensioning member 51 is provided

with a weighted arm 58 which lies over a finger 59 formed on a control lever 60 pivoted on the shaft 23 and extending over the ends of bars 61 of the chains 15, certain of said bars having a clip 62 positioned to raise the control lever 60. The cords 37 of the selected control levers are passed to the left of the upper rod 55 and to the right of the lower rod and between the rocking member 54 and the wire 57.

The cords 37 are longer than the distance between the points at which they are connected to the upper and lower levers 35 and 36 when said levers are both either raised or lowered and when it is desired to control those harnesses or boxes corresponding to the lower levers 36 which are shown to the right of Fig. 2 by the upper cylinder the tensioning device will be in the position indicated in Fig. 3, being moved to that position by lever 60 which has been raised by the clip 62. In this position the paths traversed by the cords 37 are such that there is no slackness in said cords and any upward movement of the levers 35 will be immediately communicated to the corresponding lower levers 36. When it is desired to take the lower levers 36 out of control of the upper cylinder an ordinary dobby bar 61 without the clip 62 will be presented under the lever 60 and the latter will move down and the tensioning device will rock to the position indicated in Fig. 1. In this latter position the rods 55 are practically in alignment with the points of attachment of the cords with the levers so that said cords are slack as indicated in Fig. 1. When in this position the upper levers 35 may continue to be raised by they will serve only to use up the slack of the cords and will not be able to raise the lower levers. The latter are therefore controllable by the main chain 15 independently of the upper chain.

It is to be understood that there will be as many clips 62 as there are bars on the lower chain 15 which are not pegged to control the end lower levers 36 and that there will be as many bars on the lower chain 15 without clips as are pegged for the lower levers. In other words, any of the bars of the lower chain which control all of the lower levers 36 will be made without the clip.

The harness frames which may be controlled by the upper chain are usually devoted to the side portions of such fabrics as handkerchiefs where the border runs continuously from one end of the fabric to the other. The chain illustrated in Fig. 1 for the bottom cylinder has twelve bars double index which corresponds to twenty-four picks of the loom. As shown in said figure the upper auxiliary chain is ineffective to control the harness frames, there being six bars without clips to provide twelve picks.

of one type of weft, for instance twill, which is pegged on the lower chain, and there are also six bars of the lower chain provided with clips 62 which account for twelve 5 picks to be controlled by the upper cylinder to produce another weave such, for instance, as a satin. The chains illustrated herein are very short but can be lengthened to carry out the principles described.

10 If desired the multiplier control effected by chain 29 may be omitted as has been done heretofore in actual practice, but in such a case the upper cylinder would still continue to receive a regular angular motion throughout the operation of the loom, the purpose 15 of illustrating said chain 29 being to indicate that the invention set forth herein can be used in connection with a multiplier chain.

While I have described the device in connection with a multiplicity of weaves, yet it is to be understood that the device is 20 equally applicable to the control of boxes on box looms where the boxes are controlled by certain jacks of the dobby, that is, the 25 device can be used to control either harness frames or boxes when these devices are controlled by the lower fingers 36. When applied to boxes the invention is applicable 30 to fabrics employing a crepe weave in connection with other weaves, such as twill, satin, or plain. When so used the upper cylinder can be pegged to keep one box active 35 for two picks and then another box active for two picks, alternating this control so long as crepe is being woven, this control being accomplished when the tensioning device is in the position indicated in Fig. 3. After the crepe part of the repeat has been 40 completed and it is desired to pass to another part of the repeat the tensioning device may be moved to the position indicated in Fig. 1, thus rendering the top cylinder ineffective even though the same continues to give its indications. The control, 45 passing to the lower cylinder, makes it possible to peg the lower chain 15 so as to call any other boxes including those which are controlled by the top cylinder. On a 4 x 1 loom for instance, there would be two of 50 the cords 37 assigned to boxes and controlled by the tensioning devices.

From the foregoing it will be seen that I 55 have provided a very simple means for transferring the control of a selected set of lower levers from one to another cylinder merely by tightening or slackening the flexible connections between the upper and lower levers. The rods 55 are slidable in their 60 bearings so as to embrace a varying number of cords 35 depending upon the number of harnesses which are to be given over to the side portion of the fabric being woven, and when it is desired to use the loom to 65 weave a fabric which does not require the alternate control of certain of the levers 36

said rods 55 may be removed so that the top fingers will not be effective to interfere with the indication and operation of the lower levers even though the top cylinder continues to move.

70

Having thus described my invention it will be apparent that changes and modifications may be made therein by those skilled in the art without departing from the spirit and scope of the invention, and I do not 75 wish to be limited to the details herein disclosed but what I claim is:

1. In a multiple weave motion for pattern mechanism, a main pattern chain, a main set 80 of levers therefor, a second pattern chain, a second set of levers therefor, flexible connections between certain of the first named levers and certain of the second named levers, and means to tighten or slacken said connections to render the second levers effective or ineffective, depending upon 85 whether the connections are tight or slack, to control the first named levers.

2. In a multiple weave motion for pattern mechanism, a main pattern chain, a main set of levers therefor, a second pattern chain, a second set of levers therefor, flexible connections between certain of the first named levers and certain of the second named levers, a rocking lever under control of one of the 90 pattern chains to vary the length of the path traversed by the flexible connections to the end that when said path is lengthened the second named set of levers is effective and when said path is shortened said second 95 named set of levers are ineffective to control the first named set of levers.

3. In a multiple weave motion for pattern mechanism, a main pattern chain, a main set 100 of levers therefor, a second pattern chain, a second set of levers therefor, flexible connections between certain of the first named levers and certain of the second named levers, an angularly movable device engaging opposite sides of the flexible connections and 105 under control of one of the pattern chains to slacken or tighten said flexible connections, the second named levers controlling the first named levers when said connections are tightened and moving without effect on 110 the first named levers when said connections are slackened.

4. In a pattern mechanism for looms, a main pattern surface, a main set of levers for 115 the pattern surface, an auxiliary pattern surface receiving an angular movement regularly during the operation of the loom and independently of the motion of the main pattern surface, a set of auxiliary levers for the auxiliary pattern surface, and flexible connections between the main and auxiliary levers connecting said levers together in 120 pairs, each pair having an auxiliary and a main lever, and means under control of one 125 of the pattern surfaces to render the auxil- 130

iary levers ineffective during a part of the operation of the loom to control the main levers and to render said auxiliary levers effective during another part of the operation 5 of the loom to control the main levers, said main and auxiliary levers moving at all times about fixed centers when actuated by the pattern surfaces.

5. In a device of the class described, a 10 main cylinder, a pattern surface carried thereby, a main set of levers for the pattern surface, a second cylinder receiving a regular movement during the operation of the loom independent of the movement of the main cylinder, an auxiliary pattern surface 15 for the auxiliary cylinder, a set of auxiliary levers for the auxiliary pattern surface, flexible connections between the main and auxiliary levers connecting said levers in pairs 20 so that each pair has one main and one auxiliary lever and means to cause the flexible connections to traverse a lengthened path during a portion of the operation of the mechanism to place the main lever of each 25 pair under the control of the auxiliary lever of the same pair, said means being movable to cause the flexible connections to traverse a shorter path in order to render the auxiliary lever of each pair ineffective to control 30 the main lever of the corresponding pair.

6. In a device of the class described, a main pattern surface, a main set of levers for the pattern surface, an auxiliary pattern surface receiving an angular movement reg-

ularly during the operation of the loom and 35 independently of the motion of the main pattern surface, a set of auxiliary levers for the auxiliary pattern surface, and flexible connections between the main and auxiliary levers connecting said levers together in pairs, 35 each pair having an auxiliary and a main lever, and a device operatively associated with the flexible connections and under control of one of the pattern surfaces and defining a longer path along which the flexible 40 connections move when in one position than when said device is in another position, the auxiliary lever controlling the corresponding main lever when the path is long and the auxiliary lever being ineffective to control 45 the corresponding main lever when the path is shorter.

7. In a device of the class described, a main pattern chain, a main set of levers therefor, a second pattern chain, a second set 50 of levers therefor, flexible connections between certain of the first named levers and certain of the second named levers, said connections being of such length as normally to be slack, under which conditions the main 55 levers move independently of the second set, and means to take up the slackness of the connections to cause the main levers to be under control of the second set.

In testimony whereof I have hereunto af. 60 fixed my signature.

WALTER H. WAKEFIELD.
